COMBINATION CURTAIN, SHADE, AND
DRAPE BRACKET

Vincent P. Rosage, Johnstown, Pa.

Application July 15, 1940, Serial No. 345,642

5 Claims. (Cl. 248—253)

This invention relates to brackets or holders of the type employed for holding window shade rollers, curtain and drape rods; and among the objects of the invention is to provide a holder or bracket of this character which may be used with various forms of curtains and drape rods; and which at the same time is comparatively simple in construction, can be cheaply and economically made, and can be applied to the window frame and secured in position thereon with a minimum number, two, fastening elements.

The invention together with its objects and advantages will be best understood from a study of the following description taken in connection with the accompanying drawings wherein:

Figure 1 is a front elevational view showing a window to which the holder or bracket of my invention has been applied.

Figure 2 is a perspective view of the holder or bracket.

Figure 3 is a horizontal sectional view taken substantially on the line 3—3 of Figure 2.

Figure 4 is a fragmentary detail sectional view more clearly showing the manner of securing the holder or bracket on the window frame.

Figure 5 is a plan view of the holder in blank form.

Figure 6 is a top plan view of the holder illustrating the manner of using the same for supporting gooseneck curtain rods.

Figure 7 is a sectional view through the holder or bracket, showing the manner of supporting a round curtain rod thereby, and

Figure 8 is a perspective view of one end of a relatively flat tubular curtain rod which may be supported through the use of my bracket or holder.

Referring more in detail to the drawings it will be seen that my improved bracket or holder, indicated generally by the reference numeral 5, is formed from a single blank of suitable material, such as metal or the like, cut, shaped and dimensioned to provide a substantially rectangular body portion 6 that adjacent one edge thereof is folded on a line 7 to present an attaching flange 8. The flange 8 is provided with a pair of vertically spaced apertures 9 to accommodate screws or other fastening elements 10 through the medium of which the bracket 5 is secured to the window frame or casing 11 as suggested in Figure 1. In connection with the apertures 9 it will be noted that each toward the upper end thereof tapers substantially to a point, being relatively wide at its lower end, thus permitting engagement of the bracket with the fastening elements 10, or removal of the bracket from its position on the

window casing 11 without disturbing the position of the screws or other fastening elements 10.

At the upper forward or front corner thereof 5 the body 6 of the bracket is provided with an integral lug 12 bent laterally relative to the body 6 on the fold line 13 and provided with an aperture 14 to receive, as suggested in Figure 1, the down-turned shank 15 of a drape rod 16 of conventional structure and which is generally employed for supporting side drapes for the window.

Also, adjacent the upper forward or free corner thereof, the body plate 6 of the bracket is provided with a hole 17 for receiving one end of a round drape or curtain rod such as suggested by broken lines in Figure 7 and indicated by the reference numeral 18. Generally these rods 18 are provided as suggested in Figure 7 with removable heads 18a which are removed for inserting an end of the rod through the opening 17, and after such insertion the head 18 is quickly replaced on the end of the rod.

As is known, certain curtain rods are in the form of flat tubes and embody telescoping sections, and such form of rod is suggested in Figure 25 1 by broken lines and therein indicated by the reference numeral 19.

To accommodate such forms of curtain rods, 19, the body plate 6 has pressed out therefrom to extend laterally from what may be termed the 30 inner side of the body 6, a lug 20 on which is sleeved the free end of a section of the rod 19 as suggested in Figure 1.

It is also apparent, and as shown in Figure 6, that these flat tubular telescoping curtain rods 35 are also of the gooseneck type, that is to say have their free ends bent substantially at right angles to the length of such rods, and this latter form of rod is shown in broken lines in Figure 6 and indicated by the reference numeral 21.

40 To accommodate gooseneck rods of the type shown in Figure 6 and indicated by the reference numeral 21, the flange 6 has extending at an angle thereto and substantially in parallelism with the body plate 6, upper and lower vertically spaced lugs 22.

The brackets or holders 5 will be used, of course, in pairs and one bracket or holder, in order to accommodate the round pintle of a shade roller such as shown in Figure 1 and indicated by 50 the reference numeral 23, will have suitably provided in the body 6 thereof a circular opening 24 while the body 6 of the corresponding bracket of said pair will have a portion 25, delineated substantially by broken lines in Figure 2, removed therefrom in order to provide a vertical slot open-

ing through the upper edge thereof and into which may be inserted the squared pintle of the roller 23.

Thus it will be seen that I have provided a holder or bracket whereby various forms of curtain, drape and valance rods may be supported thereby in addition to the supporting of the shade roller; and that such a bracket may be readily secured in position on the window casing with a minimum number, two, fastening elements such as screws or nails; and that further the mounting or dismounting of the bracket may be accomplished without removing or disturbing the position of such fastening elements, the elements wedging in the tapered ends of the apertures provided therefor in the flange of the bracket.

It is therefore thought that a clear understanding of the construction, manner of use, utility and advantages of a combination bracket or holder embodying the features of the present invention will be had without a more detailed description thereof.

It is also to be understood that while I have herein shown and described a preferred embodiment of the invention, it is in no wise intended to restrict the invention to the precise details of construction, combination and arrangement of parts as herein illustrated and described, other than may be required by the prior art and scope of the claims hereunto appended.

Having thus described the invention what is claimed as new is:

1. A combination curtain and shade rod bracket embodying a body plate provided at one edge thereof with a lateral apertured flange for attachment to a window casing, said plate having a plurality of separate bracket lugs formed integral therewith, and said flange at the edge thereof remote from and paralleling said plate having a plurality of separate bracket lugs formed integral therewith.

2. A combination curtain and shade rod bracket embodying a main body plate provided adjacent one edge thereof with a lateral apertured attaching flange, said body plate having extending from the upper edge thereof and adjacent the forward corner of the plate an apertured substantially horizontally disposed lug adapted to

accommodate in the aperture thereof the down-turned shaft of a drape rod; and said body plate also having struck out therefrom and extending laterally and substantially at right angles thereto a lug adapted to be engaged by one end of a curtain rod.

3. A combination curtain and shade rod bracket embodying a main body plate provided adjacent one edge thereof with a lateral apertured attaching flange, said body plate having extending from the upper edge thereof and adjacent the forward corner of the plate an apertured substantially horizontally disposed lug adapted to accommodate in the aperture thereof the down-turned shaft of a drape rod; and said body plate also having struck out therefrom and extending laterally and substantially at right angles thereto a lug adapted to be engaged by one end of a curtain rod; and said flange having an integral lug extending substantially at right angles therefrom and parallel with said body plate and adapted to be engaged with one end of a gooseneck curtain rod.

4. A combination curtain rod and shade roller bracket embodying a main body plate provided at one edge thereof with a laterally extending flange for attachment, said main body plate having adjacent an upper corner thereof a horizontal, laterally extending apertured lug for receiving the down-turned end of a drape rod; said body plate being also provided with a laterally extending curtain rod-engaging lug struck from said body plate, and said body plate having an aperture therein intermediate the first and second-named lugs for receiving one end of a round curtain rod.

5. A combination curtain and shade rod bracket embodying a body plate provided at one edge thereof with a lateral apertured flange for attachment to a window casing, said plate having a plurality of separate bracket lugs formed integral therewith, and said flange at the edge thereof remote from and paralleling said plate having a plurality of separate bracket lugs formed integral therewith, and said body plate being also provided for supporting one end of a shade roller.

VINCENT P. ROSAGE.
